ADJUSTABLE SEAT

Hugh Milton Erwin, Dallas, Tex.

Application March 5, 1936, Serial No. 67,357

5 Claims. (Cl. 155—95)

The invention forming the subject matter of this application relates to chairs, or similar supports, in which the seat may be elevated and rotated upon its axis to any desired position to 5 suit the convenience of the operator.

The object of the invention is to provide a support with a seat capable of being raised and lowered relative to the support, and locked frictionally in any desired angular position in the 10 support.

Other objects of the invention will become apparent as the detailed description thereof proceeds.

In the drawing:

15 Figure 1 is a perspective view of a seat embodying the present invention;

Figure 2 is a vertical section of the seat taken on the line 2—2 of Figure 1; and

20 Figure 3 is a section taken on the line 3—3 of Figure 2.

As shown in the drawing, the invention comprises a substantially rectangular base member 1 having a bottom 2, end walls 3 and 4, a front wall 5, and a rear wall 6. A partition 7 is suitably secured to walls of the base member substantially parallel to the bottom 2, and slightly below the top edges of the walls of the member 1.

A rectangular casing 8 is seated on the partition 7 in the recess formed thereby with the 30 walls of the base member. The casing 8 is provided with a top 9 provided with two circular apertures 10 and 11, the edges of which are bent to seat in recesses formed in the upper edges of the frusto-conical seat members 12 and 13, respectively. These members 12 and 13 form locking supports for the frusto-conical casings 14 and 15, respectively.

Each of the casings 14 and 15 has suitably secured thereto a plate 16 forming a support for 40 the springs 17 which are covered by circular sheet 18 of flexible material, such as is commonly used in upholstered chairs. The edges of these sheets are suitably secured in the recessed upper edges of the casings 14 and 15.

45 The casings 14 and 15 normally fit snugly in the members 12 and 13 and are prevented from rotation therein by their friction fit. The seats formed by the casings 14 and 15 and their associated cushions, are adapted to be raised bodily from locked contact with their supporting members 12 and 13, and to be rotated about substantially vertical axes. For this purpose, a shaft 19 is mounted to rotate in bearings 20 and 21 secured in the end walls 3 and 4.

55 Cams 22 are suitably secured to shaft 19 di-

rectly below the centers of the cushion seats; and each cam supports a rod 23 mounted to slide through an aperture 24 in the partition 7. A vertical guide 25 clamped to the partition 7 receives the rod 23 snugly and slidably to ensure 5 rotation of the cushioned seat about the axis of the frusto-conical members. The upper end of the rod 23 is provided with a heavy flange 26 which is fixed to the plate 16.

In order to effect raising and lowering of the 10 rods 23, and the seats supported thereby, the shaft 19 has a crank arm 27 projecting radially from the center thereof. A link 28 is pivotally connected at one end to the end of the arm 27; and, at its other end is pivoted to one end of a 15 lever 29. The lever 29 is pivoted between its ends to a bracket 30 fixed to the front wall 5 of the base member 1.

The cams 22 are shaped and arranged on shaft 19 so that the cushioned seats are in lowered 20 and locked position when the lever 29 lies in vertical position, as shown in full lines in Figure 3. A swing of the lever to the position shown by the dotted lines in Figure 3 rotates the shaft 19, and the cams thereon, so as to raise the seats out of 25 locked contact with the seat members 12 and 13. In raised position the seats may be rotated freely about their vertical axes to suit the convenience of the persons using them.

What I claim is:

1. A base provided with a conical recess, a rod 30 slideable and rotatable on said base coaxially with said recess, a seat fixed to one end of said rod and normally resting in said recess, and means connected to the other end of said rod to raise 35 the seat from said recess.

2. A base member having a frusto-conical recess formed therein, a guide on said base member having a bore coaxial with said recess, a rod 40 mounted to slide and rotate in said bore, a seat fixed to one end of said rod and having a frusto-conical periphery adapted to fit and be locked in said recess when the rod is in lowered position in said guide, and means for raising said rod from lowered position to move the seat from 45 said recess and permit rotation thereof.

3. A base member having a frusto-conical recess formed therein, a guide on said base member having a bore coaxial with said recess, a rod 50 mounted to slide and rotate in said bore, a seat fixed to one end of said rod and having a frusto-conical periphery adapted to fit and be locked in said recess when the rod is in lowered position in said guide, a shaft rotatable in said base member, a cam on said shaft supporting said rod, 55

and means for rotating said shaft to effect release of the seat from locked position in said recess.

4. A base member having a frusto-conical recess formed therein, a guide on said base member having a bore coaxial with said recess, a rod mounted to slide and rotate in said bore, a seat fixed to one end of said rod and having a frusto-conical periphery adapted to fit and be locked in 5 said recess when the rod is in lowered position in said guide, a shaft rotatable in said base member, a cam on said shaft supporting said rod, a lever fulcrumed on said base member, and means connecting said lever to said shaft to rotate said 10 shaft.

5. A base member having a frusto-conical recess formed therein, a guide on said base member having a bore coaxial with said recess, a rod mounted to slide and rotate in said bore, a seat fixed to one end of said rod and having a frusto-conical periphery adapted to fit and be locked in 5 said recess when the rod is in lowered position in said guide, a shaft rotatable on said base member, a cam on said shaft supporting said rod, a crank arm extending radially from said 10 shaft, a lever fulcrumed on said base member, and a link pivotally connecting said crank arm to said lever to effect rotation of said shaft.

HUGH MILTON ERWIN. 15
